ELECTRIC SWITCH

Charles E. Hanny, Plainville, Conn., assignor to
The Trumbull Electric Manufacturing Company, Plainville, Conn., a corporation of Connecticut

Application June 22, 1940, Serial No. 341,814

7 Claims. (Cl. 200—114)

My invention relates to electric switches of the so-called fuse-puller type.

One object is to provide a simple, rugged construction in which the fuse carrier contacts are so designed that the carrier may be reversed and inserted in the "off" position without the possibility of closing the circuit or injuring the parts.

Another object is to provide fuse carriers for the main and branch circuits so constructed with respect to the main holder that they cannot be interchanged.

Fig. 1 is a front view of one form of construction involving my invention.

Fig. 2 is a vertical sectional view of the same on the general plane of the line 2—2 of Fig. 1.

Fig. 3 is a transverse sectional view on the general plane of the line 3—3 of Fig. 1.

Fig. 4 is a similar sectional view showing one of the fuse carriers inserted in open circuit or "off" position.

Fig. 5 is a front view of the insulating support or body for receiving the fuse carriers.

Fig. 6 is a perspective view of the main circuit fuse carrier.

Fig. 7 is a perspective view taken from the rear of the branch circuit fuse carrier.

Figs. 8 and 9 are diagrammatic views showing typical circuit connections and indicating in dotted lines the relatively small and large openings leading to the plug-in contacts.

The current carrying parts and the supports for them are enclosed in a suitable receptacle, for instance one having a body or box portion 10 and a cover 11 hinged at one edge thereto. This cover may be held in place by screws such as 12.

The central part of the cover is provided with a depressed portion 13 which provides a recess which is normally closed by a door 14 hinged at 15 to the main cover.

In its preferred form the main features of the invention include an insulating body 16 which may be suitably secured to the base in any suitable manner as for instance by means of lugs 17 and screw 18. This body carries all of the principal conducting portions including the fuse sockets and removable fuse carriers.

The construction shown provides for the control of the main circuit and the branch circuit for which there is a main fuse carrier 20 and a branch fuse carrier 21. The electrical connections for these two carriers are alike, but the carriers are so constructed that they are not interchangeable. For this purpose it will be noted that the recess 22 is generally rectangular but 55

has opposite corners 23, 23 filled in and the corresponding corners 24 of the carrier are beveled off. In similar manner the corners 23 of the recess for the fuse carrier 21 are filled in and the corresponding corners 24 of the carrier are beveled off. By reason of this construction, it will be seen that it will be impossible to insert carrier 21 in the recess for carrier 20.

As the two carriers and the associated conductors are electrically similar, it will be necessary to describe only one.

Each of the upper circuit terminals 26 is suitably secured to the base and a spring contact 27 which projects slightly into the passage 28 in the base. Each of the lower contacts 29 is similarly constructed and projects slightly into a passage 30. In this case, the contact 29 is secured by a central screw 31 which also secures a fuse socket 32 and its terminal 33.

20 The fuse carrier is provided with contact blades 34, 34 at one end and 35, 35 at the other end. These contact blades are connected to fuse sockets such as 36 and 37, respectively, for supporting cartridge type fuses.

In the fuse shown in Figs. 1 and 2, the carrier 21 is in place in its recess in the base and the blades 34 and 35 engage respectively the contacts 27 and 29 so that the circuit will be closed or "on". To open the circuit, it is merely necessary to pull out the carrier 21 by means of the handle 38.

35 To leave the switch in the "off" or open circuit position, it is merely necessary to reverse the carrier 21 and insert it with the word "off" in the proper position as shown in Fig. 4. In this position, it is impossible for the circuit to be closed because of the fact that the edge of the blades 34, 34 has a flange 39 which cannot be inserted into the passage 30 because the passage 30 is not 40 as wide as passage 28 adjacent the contact 27.

45 By this simple arrangement and construction, it is possible to provide means for supporting the fuse carrier in the "off" position in such manner that it is impossible to close the circuit except by deliberately withdrawing the fuse carrier, inverting and reinserting it.

The other fuse carrier 20 is provided with blades 40 and 41, the latter having flanged ends 42 corresponding to the flanged portions 39 of the blades 34. The base is accordingly provided with narrow passages 43 for the blades 40 and wide passages 44 for the blades 41 having flanged extensions 42.

50 In the diagrammatic views of Figs. 8 and 9, it will be seen that the passages 43 for the pas-

sage of blades 40 are very narrow while the passages 44 for the passage of blades 41 and tips 42 are much broader. The reason for providing this arrangement is to prevent any connection with the "live" parts except when intentionally inserting the flat blade 40. The contact 27 on the "line" side is the "live" contact whereas the contact 29 is on the branch side of the circuit. It is accordingly impossible to force the blade 41 with its foot 42 into engagement with the "live" contact 27 even though it might be possible to insert the blade 40 into the passage 44 and against the contact 29.

A similar situation in Fig. 8 exists on the right hand side where the contacts 29', 29' are connected by cross conductors 50 to the line wires 51 and 52 so that the contacts 29' are the live contacts of the "range" side. For this reason the passages 30 in the base are made narrower than passages 28.

Fig. 9 shows a simple diagram where the narrow passage 43 is provided adjacent the live contact 27 and the wider passage 44 is provided adjacent the branch contact 29.

Similarly on the right hand side of Fig. 9 the "range" circuit includes stationary contacts 29 which are connected by cross members 53 and 54 to the respective contacts for the main fuses.

When the main circuit is closed the contacts 29, 29 on the right are the live contacts in the "range" circuit and accordingly I provide narrow passages 30, 30 adjacent those contacts 29, 29 to receive the blades 35, 35, which passages are too narrow to receive the blades 34, 34.

The base may be suitably marked "on" at its top portion and "off" at its bottom portion to assist in guiding the carrier to desired position.

It will be noted that when a carrier is in either an "on" or "off" position in its recess, the switch contacts, fuse clips, fuses and all current carrying parts are inaccessible and shielded against all outside contact.

The improved switch is neat and compact and is so made and marked that mere reversal of either carrier, top for bottom, gives complete contact or none at all, thus eliminating all guess work and making the switch practically fool proof.

When in the "off" position, the contact blades such as 34 and 35 and 40 and 41 may resiliently and frictionally engage side walls of the chamber so as to prevent the carrier from falling out or rattling.

I claim:

1. A puller type switch including a base with two substantially rectangular recesses for receiving carrier blocks, each block when entirely inserted in one position closing the circuit and when inverted adapted to be inserted substantially in its entirety without reestablishing the circuit, said recesses having corners protruding therein and adapted to be engaged by the corners of the block for preventing interchangeability of the blocks in the recesses in closed circuit position.

2. A puller type switch having an insulating base with protected switch contacts and with a pair of passages of a certain size and another pair of passages of a larger size and a reversible insulating carrier block insertible into the base and having a pair of blades adapted to be inserted into the pair of smaller passages and having another pair of blades with flanges insertible into the larger passages to establish a circuit but too large to be inserted into the smaller passages whereby the block cannot be inverted and insert-

ed to reestablish the circuit, and whereby the correct position for complete insertion of said block may be easily and rapidly ascertained by inspection of said flanged blades and said larger sized passages.

3. In a pull type switch having an insulating base carrying at least two separated contacts below one surface of the base and a separate removable and reversible block carrying at least two cooperating blades in a single circuit, an arrangement for allowing cooperation of the blades with the base contacts to complete a circuit between the contacts in one position of the block and to prevent completion of the circuit in another position of the block, including a flange at the tip of one of the blades, and a cooperating surface on the base above one of the contacts, preventing engagement of the flanged blade with that contact, the base above the other of said contacts being free from contact preventing surfaces, said flange and said cooperating raised surface affording upon visual and tactile inspection, rapid and easy determination of the relative position of said base contacts and said block blades with respect to complete engagement with one another.

4. In a pull type switch having an insulating base carrying a line contact and a load contact below a surface of the base and a separate removable and reversible block carrying at least two blades in a single circuit, an arrangement for allowing cooperation of the blades with the base contacts to complete a circuit between the line and load in one position of the block and to prevent completion of the circuit in another position of the block, including a flange at the tip of one of the blades and a cooperating surface on the base above the line contact, preventing engagement of the flanged blade with that contact, the base above the load contact being free from any such contact preventing surfaces, whereby the determination of the position in which said flanged blade may engage the load contact is easily accomplished.

5. A puller type switch having an insulating base with protected switch contacts and with a pair of passages of a certain size and another pair of passages of a larger size and a reversible insulating block insertible into the base and having a pair of line blades and a pair of load blades with flanged portions, said line blades being adapted to be inserted into the pair of smaller passages and said load blades being adapted to be inserted into said larger passages to establish a circuit but being too large to be inserted into said smaller passages whereby the block cannot be inverted and the blades inserted to reestablish the circuit.

6. In a pull type switch having an insulating base carrying a line contact and a load contact below a surface of the base, and a separate removable and reversible block carrying at least two blades in a single circuit, one of said blades being formed with a flange at its tip, an arrangement for allowing cooperation of the blades with the base contacts to complete a circuit between the line and load in one position of the block and to prevent completion of the circuit in another position of the block including a passage in the base above the line contact and a passage in the base above the load contact, the passage above the line being too small to receive the blade with the flanged tip but sufficiently large to receive the other blade, the passage above the load con-

tact being sufficiently large to receive the blade with the flanged tip.

7. A puller type switch including a base having two recesses each provided with fixed contacts and each being substantially rectangular in cross section, one recess having two predetermined opposite corners filled in and the other recess having filled in the two opposite corners not correspondent to the filled in corners of said first recess, two fuse carrier blocks, the first block having cut away corners corresponding to the filled in corners of the first recess and the second block

5 having cut away corners corresponding to the filled in corners of the second recess, whereby each of said blocks can enter only the respective recess having corresponding corner configurations, but said block can enter said recess in two positions angularly removed by substantially 180°, each of said blocks carrying contact blades so formed and adapted as to connect the fuses carried by said block to the contacts in the recess when it enters therein at one predetermined angular position only.
